UNITED STATES PATENT OFFICE.

PERLEE W. SCHOFIELD, OF MARION, INDIANA, ASSIGNOR TO STANDARD GLASS COMPANY,
A CORPORATION OF INDIANA.

DESIGN FOR A BOTTLE.

No. 39,479.

Specification for Design.

Patented Sept. 1, 1908.

Application filed June 17, 1908. Serial No. 439,068. Term of patent 7 years.

To all whom it may concern:

Be it known that I, PERLEE W. SCHOFIELD, a citizen of the United States, and residing at Marion, in the county of Grant and State of Indiana, have invented a certain new, original, and ornamental Design for a Bottle, shown in the accompanying drawing, which is a view in perspective of the same.

I claim:—

The ornamental design for a bottle, as shown.

PERLEE W. SCHOFIELD.
